*Primary Examiner—Bernard Ansher**Assistant Examiner—M. Siegel***[57]****CLAIM**

The ornamental design for a combination liquid container and toy building block, as shown.

DESCRIPTION

FIG. 1 is a top perspective view of a combination liquid container and toy building block showing my new design;

FIG. 2 is a bottom perspective view thereof;

FIG. 3 is a right side elevational view thereof;

FIG. 4 is a top plan view thereof;

FIG. 5 is a front elevational view thereof;

FIG. 6 is a bottom plan view thereof;

FIG. 7 is a rear elevational view thereof; and,

FIG. 8 is a left side elevational view thereof.
